US00D791337S

(12) **United States Design Patent** (10) Patent No.: **US D791,337 S**
(45) Date of Patent: ** Jul. 4, 2017

(54) **TUBE RACK TOOL**

- (71) Applicant: **BioFire Defense, LLC**, Salt Lake City, UT (US)
- (72) Inventors: **Logan M. Taylor**, West Haven, UT (US); **Richard David Abbott**, Draper, UT (US)
- (73) Assignee: **BioFire Defense, LLC**, Salt Lake City, UT (US)

(**) Term: **15 Years**

(21) Appl. No.: **29/555,675**

(22) Filed: **Feb. 24, 2016**

(57) **CLAIM**

The ornamental design for a tube rack tool, as shown and described.

DESCRIPTION

FIG. 1 is a perspective view of a tube rack tool;
FIG. 2 is a perspective exploded view of the base and top portion of a tube rack tool;
FIG. 3 is a front elevation exploded view thereof;
FIG. 4 is a rear elevation exploded view thereof;
FIG. 5 is a right side elevation exploded view thereof;
FIG. 6 is a left side elevation exploded view thereof;
FIG. 7 is a bottom plan exploded view thereof; and,
FIG. 8 is a top plan exploded view thereof.

The broken lines depicted in FIGS. 1-8 illustrate portions of the tube rack tool that form no part of the claimed design.

1 Claim, 8 Drawing Sheets
